DESIGN FOR A CAN OPENER

James Harvey Chandler, Oak Park, and Myron Jackson Zimmer, Wooddale, Ill., assignors to Ecko Products Company, Chicago, Ill., a corporation of Illinois

Application April 9, 1945, Serial No. 118,923

Term of patent 14 years

(Cl. D22—2)

To all whom it may concern:

Be it known that we, James Harvey Chandler and Myron Jackson Zimmer, citizens of the United States, residing at Oak Park, in the county of Cook and State of Illinois, and at Wooddale, in the county of Du Page and State of Illinois, respectively, have invented a new, original, and ornamental Design for a Can Opener, of which the following is specification, reference being had to the accompanying drawing, forming part thereof.

Fig. 1 is a side elevational view of a can opener, showing our new design.

Fig. 2 is a top plan view of the same.

Fig. 3 is a fragmentary side elevational view thereof, when turned about an upright axis through an angle of 90 degrees relative to the position shown in Fig. 1, a portion of the operating handle being shown broken away for convenience of illustration.

The dominant feature of the design resides in the portion shown in full lines.

We claim:

The ornamental design for a can opener, as shown and described.

JAMES HARVEY CHANDLER.
MYRON JACKSON ZIMMER.
